UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,908, dated November 14, 1893.

Application filed October 9, 1893. Serial No. 487,674. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification.

The design consists of an arrangement of ornamental scrolls forming lyre-shaped panels with festoons and sprays of flowers and leaves hanging from said scrolls, and an oval ribbon wreath suspended from said scrolls and in which is perched a dove, as represented in the accompanying drawing.

The border or upper portion of the design is formed of ornamental scrolls forming lyre-shaped panels with bunches of flowers and leaves arranged in the center of said panels and festoons of flowers and leaves hanging below said panels as shown in the drawing. ²⁰ The ornamental panels are connected by lyre-shaped ornaments and festoons of flowers and leaves forming a continuous border as shown.

What I claim is—

1. The design for wall paper herein shown ²⁵ and described.
2. In the design for wall paper, the border herein shown and described.

Witness my hand this 5th day of October, 1893.

CHARLES BOOZE.
